UNITED STATES PATENT OFFICE.

FRANK V. MOORE, OF CHICAGO, ILLINOIS, ASSIGNOR TO CURRIER PUBLISHING COMPANY, OF CHICAGO, ILLINOIS, A CORPORATION OF ILLINOIS.

DELIVERY FEED MECHANISM FOR MAILING-MACHINES.

1,060,276.

Specification of Letters Patent.

Patented Apr. 29, 1913.

Application filed January 12, 1912. Serial No. 670,943.

To all whom it may concern:

Be it known that I, FRANK V. MOORE, a citizen of the United States of America, and resident of Chicago, Cook county, Illinois, 5 have invented a certain new and useful Improvement in Delivery Feed Mechanism for Mailing-Machines, of which the following is a specification.

My invention relates to mailing machines 10 of that character in which means are provided for folding and wrapping the magazines, pasting the wrappers, and then addressing the wrapped magazines.

My invention relates more particularly to 15 the means for feeding the magazines from the pasting mechanism to the addressing mechanism. This has been done in various ways, but the feed mechanism heretofore employed for this purpose has not been entirely satisfactory.

The object of my invention is, therefore, 20 to provide a novel and highly efficient feed mechanism for transferring the wrapped magazines from the pasting mechanism to the addressing mechanism of a mailing machine of this general character.

To this and other useful ends, my invention consists in matters hereinafter set forth and claimed.

30 In the accompanying drawings, Figure 1 is a plan of that portion of a mailing machine which involves the pasting and addressing devices, showing a feed mechanism embodying the principles of my invention.

35 Fig. 2 is a vertical longitudinal section on line 2—2 in Fig. 1. Fig. 3 is a vertical transverse section on line 3—3 in Fig. 2. Fig. 4 is a detail plan of the bearings at one side of the feed mechanism. Fig. 5 is an enlarged section on line 5—5 in Fig. 3. Fig. 6 is a vertical section on line 6—6 in Fig. 5. Fig. 7 is a vertical section on line 7—7 in Fig. 6. Fig. 8 is an axial section of one of the upper feed rolls, showing a portion of 45 the arbor in elevation.

As thus illustrated, my invention comprises a pasting mechanism A of any suitable, known or approved character, having an ejector α adapted to deliver the wrapped 50 magazines to the inner end of the table B. The outer end of this table has an addressing mechanism C of any suitable, known or

approved character. As there are various well-known forms of pasting, and also addressing, mechanism, no further description 55 thereof is necessary.

The feed mechanism for transferring the wrapped magazines from the pasting mechanism to the addressing mechanism is constructed as follows: Bearings b are 60 mounted on the under side of the table B for the two shafts b' which extend transversely of the machine and are spaced a suitable distance apart. The said table is also provided with four slots b^2 in which rotate the rolls b^3 on said shafts. These rolls are mutilated for one half their circumference—that is to say, are reduced in diameter to that extent, whereby each roll is in effect only a segment of a roll. The two 70 bearings b^4 are mounted on the top of the table, and outside of the said slots and rolls. Each said bearing b^4 has upright end portions which are provided with longitudinal slots b^5 each of which is intersected by a 75 transverse slot b^6 . The ends of the arbors b^7 are flattened to engage the slots b^6 , and the ends of the two arbors are connected by bars b^8 that rest in the slots b^5 . Upright rods b^9 have their lower ends fastened in 80 the bearings b^4 , and extend upward through openings in the bars b^8 . Springs b^{10} are interposed between the tops of said bars b^8 and the nuts b^{11} on the upper ends of said rods, whereby the bars b^8 and arbors b^7 are 85 held yieldingly down. The arbors b^7 are provided with enlargements b^{12} having circumferential grooves b^{13} . The rolls b^{14} are mounted to rotate on said enlargements b^{12} , and are provided with screws b^{15} that engage 90 said grooves, whereby said rolls are held against lateral displacement. Each roll b^{14} is directly over a roll b^3 , whereby the feed mechanism comprises a plurality of sets of upper and lower feed rolls. The 95 rolls b^3 are preferably so disposed on the two shafts that the feed rolls nearest the pasting mechanism lets go of the magazine immediately before the second set of rolls takes hold thereof.

100 To keep the wrapped magazines down flat upon the table B, the arbors b^7 are provided with parallel shoes or runners b^{16} that bear upon the magazines as they pass along. The

shoes are hung on screws b^{17} that extend vertically through holes in the said arbors, and thumb nuts b^{18} are applied to the upper ends of said screws to hold them in place. 5 Springs b^{19} are interposed between the said shoes b^{15} and the arbors b^7 , whereby each shoe is adapted to move up and down while the magazines are passing under them. These shoes are disposed inside of the feed 10 rolls. The said rolls may be driven in any suitable manner. As shown, the shafts b^9 are provided with sprockets b^{20} which engage the same sprocket chain b^{21} , which latter is driven by a sprocket b^{22} on the drive 15 shaft b^{23} , an idler sprocket b^{24} being disposed in the slack or bend of the said chain below the second set of feed rolls. With this arrangement the rolls are operated and the relation between them is preserved. As 20 only the lower rolls are positively driven, the upper rolls operate as idlers, and are rotated by engagement with the passing magazines. In a certain sense, the upper rolls are mounted to float on the stream 25 of folded and wrapped magazines passing from the pasting mechanism to the addressing mechanism.

With the arrangement thus shown and described, the magazines are taken from the 30 pasting mechanism and moved or fed along in an orderly and certain manner to the addressing mechanism. As the feed mechanism for doing this is of a rotary character, it follows that the machine may be run 35 at high speed without objectionable results in the feeding of the magazines to the addressing mechanism. The mutilated rolls b^3 are preferably roughened on their engaging surfaces to more effectively feed the 40 magazines. As stated, the first set of rolls releases the magazine a moment before it is taken hold of by the second set of rolls. This mode of operation gives good results, but the rolls may be adjusted and spaced in 45 various ways and in accordance with the character of the work. Also, any suitable number of sets of feed rolls may be employed without departing from the spirit of my invention.

50 I do not, of course, limit myself to the exact construction shown and described, nor to the use of my invention in a mailing machine, as it can be used for other purposes without departing from the spirit of my 55 invention.

What I claim as my invention is:—

1. In a mailing machine, a feed mechanism for the wrapped magazines, comprising a plurality of sets of feed rolls, a table 60 across which the wrapped magazines are moved by said rolls, arbors for the upper rolls, means for mounting said arbors against rotation with the rolls, and shoes mounted on said arbors and bearing down 65 on the passing magazines.

2. In a mailing machine, a feed mechanism for the wrapped magazines, comprising a plurality of sets of feed rolls, and a table across which the wrapped magazines are moved by said rolls, the upper rolls having non-rotary arbors, enlargements on 70 said arbors, each enlargement having a circumferential groove, and means engaging said grooves to hold the said upper rolls against lateral displacement, but permitting 75 rotation thereon.

3. In a mailing machine, a feed mechanism for the wrapped magazines, comprising a plurality of sets of feed rolls, and a table across which the wrapped magazines 80 are moved by said rolls, the upper rolls having non-rotary arbors, supports for the ends of said arbors, preventing rotation thereof, bars resting on the said arbors, each bar reaching from one arbor to another, and 85 springs for yieldingly holding said bars against displacement.

4. In a mailing machine, a feed mechanism for the wrapped magazines, comprising a plurality of sets of feed rolls, a table 90 across which the wrapped magazines are moved by said rolls, the upper rolls having non-rotary arbors, enlargements on said arbors, each enlargement having a circumferential groove, means engaging said 95 grooves to hold the said upper rolls against lateral displacement, but permitting rotation thereon, and shoes in the form of runners yieldingly mounted on said arbors and bearing down on the magazines. 100

5. In a mailing machine, a feed mechanism for the wrapped magazines, comprising a plurality of sets of feed rolls, a table across which the wrapped magazines are moved by said rolls, the upper rolls having 105 non-rotary arbors, supports for the ends of said arbors, preventing rotation thereof, bars resting on the said arbors, each bar reaching from one arbor to another, springs for yieldingly holding said bars against displacement, and shoes in the form of runners 110 yieldingly mounted on said arbors and bearing down on the magazines. 110

6. In a mailing machine, a feed mechanism for the wrapped magazines, comprising a plurality of sets of feed rolls, and a table across which the wrapped magazines are moved by said rolls, the upper rolls having non-rotary arbors, enlargements on said arbors, each enlargement having a circumferential groove, and means engaging said 115 grooves to hold the said upper rolls against lateral displacement, but permitting rotation thereon, each said arbor being free to rise bodily or at either end thereof. 120

7. In a mailing machine, a feed mechanism for the wrapped magazines, comprising a plurality of sets of feed rolls, a table across which the wrapped magazines are moved by said rolls, the upper rolls having 125

non-rotary arbors, supports for the ends of said arbors, preventing rotation thereof, bars resting on the said arbors, each bar reaching from one arbor to another, and springs for yieldingly holding said bars against displacement, each said arbor being free to rise bodily or at either end thereof.

Signed by me at Chicago, Ill., this 9th day of January 1912.

FRANK V. MOORE.
